METHOD OF WEAVING A PILE FABRIC

Henry F. Nowicki, Norristown, Pa., and Harry J. Smiley, Glasgow, Va., assignors to James Lees and Sons Company, Bridgeport, Pa., a corporation of Pennsylvania

Application July 10, 1958, Serial No. 747,751

4 Claims. (Cl. 139—403)

This invention relates to an improved woven pile fabric of the velvet or Wilton type having a draw which produces a novel fabric effect and construction.

The primary object of the invention is to provide in a velvet or Wilton type pile fabric a simulated leno effect.

A further object of the invention is to provide in a velvet or Wilton type pile fabric a construction in which the pile yarns are bound into the base fabric in a zig-zag manner.

A further object of the invention is to provide a method of drawing in the warp yarns in a velvet or Wilton type fabric construction in which pairs of chain warps are separated by one or more pile warps in each dent.

Other objects will be apparent from the specification and drawings in which:

Fig. 1 is a schematic top view of a fabric constructed in accordance with the present invention,

Fig. 2 is a warpwise section as seen at 2—2 of Fig. 1, Fig. 3 is a weftwise section as seen at 3—3 of Fig. 1, Fig. 4 is a diagram illustrating the draw for the fabrics of Figs. 1—3,

Fig. 5 is a top view of a variation of the fabric of Fig. 1, Fig. 6 is a draw of the fabric of Fig. 5,

Fig. 7 is a warpwise section showing the fabric of Figs. 1—3 woven over pile wires,

Fig. 8 is a weftwise section of the fabric of Fig. 7,

Fig. 9 shows the fabric of Fig. 7 in a cut pile construction,

Fig. 9a is a diagrammatic illustration of the manner in which long and short pile projections are provided in accordance with the invention,

Fig. 10 is a weftwise section of the fabric of Fig. 9,

Fig. 11 is a further modified top view of a fabric constructed in accordance with the invention,

Fig. 12 shows the draw for the fabric of Fig. 11,

Fig. 13 is a further modification in which two pile yarns work together,

Fig. 14 is a schematic top view of a fabric woven in accordance with the invention in which pairs of face pile yarns in each dent carry over two successive pile wires,

Fig. 15 is a warpwise section as seen at 15—15 of Fig. 14,

Fig. 16 is a weftwise section as seen at 16—16 of Fig. 14,

Fig. 17 is the draw for the fabric as seen in Figs. 14—16,

Fig. 18 is a modification of Fig. 14 and analogous to Fig. 5,

Fig. 19 is the draw for the fabric of Fig. 18,

Fig. 20 is a diagrammatic top view of another embodiment of the invention,

Fig. 21 is a warpwise section as seen at 21, 21 of Fig. 20,

Fig. 22 is a weftwise section as seen at 22—22 of Fig. 20,

Fig. 23 is a further embodiment of the invention, and

Fig. 24 is a warpwise section as seen at 24—24 of Fig. 23.

The invention comprises essentially the provision of a pile fabric in which certain of the pile warps are tied in at warpwise staggered points in and around the fabric. This is accomplished by re-arranging the conventional draw of a velvet or Wilton fabric so that the stuffer and face yarn harnesses (in a velvet loom) work together, but the stuffer warps and the face yarn warps are separated by at least one chain warp, and single chain warps working oppositely are drawn on either side of one or more pile warps.

Referring now more particularly to the drawings, Figure 1 is illustrative of a fabric which is shown as a flat weave in order to more clearly illustrate the zig-zag course of the face yarns. Face yarns 30, 31, 32, 33, and 24 are bound in under alternate filling shots or wefts 35, 36, 37, 38, 39, and 40. Chain warps 41—50 interweave with the filling shots 35—40 and form the ground fabric together with stuffer warps 51, 51. The fabric of Figs. 1—3 also has the usual bottom filling shots or wefts 52, 52 as shown in Figs. 2 and 3. It will be noted, referring to Fig. 1, that face warp 30 follows a wavy or zig-zag course warpwise of the fabric since it is alternately tied down over the two chain warps 41 and 42 and under alternate filling shots 35, 37, and 39.

The standard manner of weaving such a fabric would be to have each of the face warps 30—34 run in a relatively straight line completely to one side or the other of pairs of chain warps 41 and 42. The novel leno effect provided by the present invention is such that the face or pile warps cross over or are positioned above the chain warps of a pair at the point where the chain warps cross each other. It will be noted in Fig. 1 that warps 30 and 31 are 180° out of phase in their warpwise course. The draw through the loom harnesses by which this weave is accomplished is shown in Fig. 4 in which the upper line represents a harness 53 carrying chain warps 41, 44, 45, 48, and 49. Harness 54 carries alternate chain warps of each pair, namely, 42, 43, 46, 47, and 50. The stuffer harness 55 carries the stuffer warps 51, 51 on the same harness in each dent since the stuffer warp is always between the top shots 35—40 and the bottom shots, 52, 52. The face pile or print harness 56 carries the face warps 30—34. It is important to note that the stuffer and print harnesses work together and may be physically attached to one another. However, the weftwise spacing of the warps is such that in each dent a pair of oppositely working chain warps, for example, 41 and 42 are separated by a pile warp 30. This draw is shown clearly in Fig. 4 and will provide the out-of-phase relationship for the pile warps shown in Figure 1. This is because the stuffer and pile warp harnesses work four times for every two reversals of the chain harnesses 53 and 54. An explanation of this statement will be clearly understood by referring to Figure 2 from which it will be noted that both the top shots 35—40 and the bottom shots 52, 52 are inserted in pairs without reversal of the chain warps. However, the stuffer and the pile warps must be inserted first underneath a top shot and then over a bottom shot. It will thus be seen that each time one of the face warps 30 is raised, first one and then the other of the chain warp harnesses 53 and 54 is raised but never the same one in succession. It is believed that this accounts for the zig-zag or leno effect because each pile warp is tied down under a top shot together with and over alternate chain warps.

Figs. 5 and 6 illustrate a variation of the weave of Figs. 1—3 in which two adjacent face warps 60 and 61 work in phase with each other so that they are both

displaced in the same direction under every top shot 35a-40a.

For weaving a pile fabric the face warps 30-34 (Fig. 1) are actually woven over pile wires 62, 62 (Fig. 7) so that the point at which the face or pile warps across adjacent pairs of chain warps is in practice elevated above the ground fabric rather than as shown in Fig. 2. In the event an uncut pile fabric is to be produced, the wires 62 will be withdrawn leaving uncut loops of the type shown in Fig. 7 but in a more relaxed and flattened condition. If the wires 62 are provided with knives, the pile loops or projections 63 will be cut to form tufts 64 and 65 as seen in Figures 9 and 10.

The withdrawal of the cutting wires has been found to produce a novel and unexpected result since with the weave of the invention tufts are formed which are not all of the same height. Since the pile yarns do not run directly across the wires as seen in Fig. 8, the withdrawal of the wires with the knives at their ends displaces the loops 63 so that a short projection 66 and a long projection 67 is formed whenever a loop is cut (Fig. 9a). Accurately speaking, the different height tufts are not J tufts in which one leg of the same tuft is longer than the other leg. The tufts in accordance with the present invention do give a J effect but this is provided by the formation of high and low U tufts which are alternately formed warpwise of the fabric as shown in Fig. 9. Weftwise of the fabric the tufts alternate from high to low whereas warpwise there will be two highs and two lows. The relative height of the tufts can be increased by other expedients such as the use of high and low wires and weaving over double wires as shown in Gebert Patent No. 2,571,860. This appearance in a cut pile fabric is considered highly desirable to provide a textured appearance and to break up lines or streakiness.

The leno type weave with the split chain draw described above can be advantageously utilized to provide a wide range of novel and desirable effects in a pile fabric. For example, the leno type weave shown in Fig. 5 as applied to a single pile yarn may be equally used with two pile yarns 70 and 71 working together as shown in Fig. 13. This has the effect of accentuating the leno or zig-zag path of the pile yarns. Coverage for the ground material in the weave of Fig. 13 may, if desired, be provided through the use of a conventional straight pile yarn 72 which is tied down under either every top shot 73 or under every other top shot as shown in Figure 13. In the latter case, pile yarn 72 is carried over two successive pile wires 62, whereas the pile yarns 70 and 71 are tied down under every top shot therefore being carried over the pile wires individually.

The "leno" weave also provides a novel and interesting effect when applied to the double wire weave shown in the Gebert patent mentioned above. In Figure 14 the dovetailing of the base loop portions 75, 75 of pile warps 76 and 77 is definitely accentuated when the pile warps split the chain warps 78 and 79 as shown in the draw of Figure 17. Figure 16 clearly illustrates the manner in which one of the chains, for example, 78 weaves over top shot 80 and to one side of pile warp 76. The other chain warp 79 of the pair simultaneously weaves under the bottom shot 81. This permits a denser weave and closer spacing of the warps along and above the top shots 80. Since the height of the pile loops 76 and 77 is preferably the same, it will be understood that the surface of the pile as seen in Figure 16 will be very dense and compact when it is appreciated that the weftwise spacing of the chain warps shown in Fig. 16 has been greatly enlarged. In other words, if the base portion of the fabric of Fig. 16 were to be compressed to its normal condition, the top portions of the loops 76 and 77 would be forced into a very confined area and thereby create substantial lateral or weftwise pressure in the upper areas of the loops.

Figure 18 shows a further variation in which the pairs

of warps in adjacent dents work in phase instead of 180° out of phase as shown in Fig. 14. The in-phase draw is illustrated in Fig. 19 and may be readily compared with the draw of Fig. 17 to illustrate the difference. In all the draw diagrams, the horizontal lines represent harnesses, the upper two being the chain harnesses, usually called front and back, and the lower two being the stuffer or print harnesses.

Figs. 11-24 are illustrative of variations and modifications of the invention showing the judicious and beneficial combination of both double wire, single wire, in phase, and out of phase construction. For example, in Figure 11 the pile warps 82 and 83 operate in leno fashion 180° out of phase since they are both carried on the print harness 84. The stuffer harness 85 in the weave of Fig. 11 is provided with a pile yarn 86 which works with the stuffer and provides a cover for the stuffer which is particularly important in the out-of-phase construction.

Figure 20 shows a draw in which two pile yarns 90 and 91 form a conventional double wire weave of the type disclosed in the Gebert patent. These yarns run together in each dent between pairs of opposed chain warps 92 and 93. However, a single pile yarn 94 may be lenoed with chain warps 92 and 93 to provide a compound or accentuated zig-zag effect either in phase or out of phase with warps 90 and 91. Warp 94 is out of phase with warp 91 but the next succeeding lenoed pile warp 95 is in phase with warp 90. Single or double binder warps 96, 96 may, if desired, be used in addition to the double binder warps 92 and 93. The combined double wire weave of Fig. 20 using a two frame double wire construction plus the single leno weave in which one pile warp works over every wire is indicated more clearly in Figs. 21 and 22.

A further variation of the weave is shown in Figs. 23 and 24 which utilizes a normal or straight warp 100 in a Wilton weave. Warp 100 works over a pair of pile wires at 101 to form a high float shown clearly in Fig. 23. Otherwise, pile 100 is carried in the back or runs dead until called for by the jacquard. The other pile warp 102 of the pair also works over two adjacent pile wires at 101 whereupon it is then carried in leno fashion by appropriate punching of the jacquard cards to tie in first under top shot 103 with chain warp 104 under the shot and chain warp 105 over the shot. At the next top shot pile warp 102 is now tied in under weft 106 but this time the chain warps 104 and 105 are reversed so that the warp 102 is displaced weftwise to provide the zig-zag weave shown. It will be noted in Figure 23 that pile 107 carries the leno weave throughout the length of the showing, whereas double high floats may be called for at 108 and 109 in accordance with the pattern and the manner in which the jacquard cards are cut.

Our improved draw which resembles a leno weave may be advantageously employed in a wide variety of velvet and Wilton weaves. By using separate weftwise spaced heddles to carry the stuffer and one of the pile yarns so that one set of chain warps can be drawn between the stuffer and the pile yarn, we achieve a very novel and desirable effect. A dense fabric can be provided with far superior coverage using less expensive face yarn.

Having thus described our invention, we claim:

1. The method of weaving a pile fabric having pairs of adjacent chain warps and pile warps which comprises the steps of raising one chain warp of each pair, lowering the other chain warp of each pair, inserting a filling weft, raising the pile warp, inserting a second filling weft and a pile wire, reversing the chains, lowering the said pile warp across the point of chain reversal, and inserting a filling weft.

2. The method of weaving a pile fabric having pairs of adjacent chain warps and pile warps which comprises the steps of raising one chain warp of each pair, lowering a pile warp, inserting a filling weft, raising the pile warp, inserting a second filling weft and a pile wire, re-

versing the chain warps, crossing the pile warp over the chain warps at the point of chain warp reversal, and tying the face pile warp in under a filling weft on opposite sides of the chain warp of each pair.

3. The method of claim 2 including the step of withdrawing the pile wire to cut the face pile warp into U tuft heights having equal legs and different height.

4. The method of claim 2 including the step of selecting face pile warps to cross pairs of chain warps at points of reversal.
